CONDITION RESPONSIVE DEVICE

Wallace A. Monson, Golden Valley, Minn., assignor to Honeywell Inc., Minneapolis, Minn., a corporation of Delaware

Filed Oct. 23, 1968, Ser. No. 14,135

Term of patent 14 years

Int. Cl. D10—07
U.S. Cl. D52—7

FIGURE 1 is a front view of a condition responsive device embodying the new design;

FIGURE 2 is a side view as seen from the right side of the device, the left side being substantially a mirror image thereof;

FIGURE 3 is a fragmentary cross-sectional view taken generally along line 3—3 of FIGURE 1; and

FIGURE 4 is a top view of the device.

The back and bottom of the device are essentially plain.

The dominant features of the design reside in the portions shown in full lines.

I claim:

The ornamental design for a condition responsive device, substantially as shown and described.
